UNITED STATES PATENT OFFICE.

WILLIAM B. SMITH AND VERA D. SMITH, OF DETROIT, MICHIGAN.

TUBE CONNECTION FOR HOT-WATER BOTTLES.

1,287,490.

Specification of Letters Patent. Patented Dec. 10, 1918.

Application filed September 4, 1917. Serial No. 189,442.

To all whom it may concern:

Be it known that we, WILLIAM B. SMITH and VERA D. SMITH, citizens of the United States of America, residing at Detroit, in the county of Wayne and State of Michigan, have invented certain new and useful Improvements in Tube Connections for Hot-Water Bottles, of which the following is a specification, reference being had therein to the accompanying drawings.

This invention relates to a tube connection for hot water bottles, and our invention aims to furnish a hot water bottle with a novel connection for the end of a tube or hose so that the tube or hose can be conveniently used without any danger of the same twisting, breaking or cracking at its connection with a hot water bottle.

Our invention further aims to provide a simple, durable and inexpensive tube connection for a hot water bottle or similar receptacle that permits of the tube being easily and quickly detached so that a stopper or plug may be substituted therefor, when it is desired to use the hot water bottle without the tube or syringe attachment.

Our invention will be hereinafter specifically described and then claimed, and reference will now be had to the drawing, wherein—

Figure 1 is a side elevation of a hot water tube, partly broken away and partly in section, showing the tube connection therewith, and

Fig. 2 is a side elevation of a modified form of connection.

In the drawing, the reference numeral 1 denotes a conventional form of hot water bottle having one end thereof provided with a filling funnel 2 and a tab 3, and the closed end with a tab 3^a. Fixed in the funnel 2 is a plug 4. The plug 4 is made of fiber, wood or any suitable material, and a neck 5 of the bottle 1 is held in engagement with the concave wall of the plug 4 by wrappings of cord, wire or other clamping means generally designated 6.

The plug 4 is provided with the central opening 7 and the outer end of the opening 50 is enlarged to receive a metallic sleeve 8 of less depth than the enlarged outer end of the opening 7. The inner walls of the sleeve 8 are screwthreaded and are adapted to receive an exteriorly screwthreaded gland 9 having a head 10. The gland 9 and the head 10 have a longitudinal bore 11 pro-

viding clearance for the end of a syringe tube 12. The inner end of the syringe tube 12 is provided with a peripheral flange 13 and interposed between said flange and the gland 9 is a fiber washer 14. This washer prevents the flange 13 from being unnecessarily worn by contacting with the inner end of the gland 9, particularly when the gland is screwed too tight or far into the sleeve 8. 65 With the gland 10 properly positioned, the flange 13 will permit of the tube 12 turning in said gland, and in this manner said tube is not twisted, cracked or broken at the gland while the syringe is being manipulated.

The head 10 permits of the gland 9 being tightened when it is desired to compress the flange 13 in the plug 4 and thus positively 75 anchor the tube 12 relative to said plug and avoid any leakage around the flange 10 of the tube, should such leakage occur.

In Fig. 2 of the drawing, there is illustrated a slight modification of our invention, wherein a nipple 15 extends through a plug 16 and is provided with a peripheral flange 17. A washer 18 is interposed between the flange 17 and the plug 16 and the outer end of the nipple 15 terminates in a button 19, so that a section of hose or tubing 85 may be fitted over the nipple.

When it is desired to use the hot water bottle without the tube connection, an ordinary screw plug, such as generally used in the filling funnel 2, can be screwed into the 90 sleeve 8 to close the plug 4.

While in the drawings, there are illustrated the preferred embodiments of our invention, it is to be understood that the structural elements are susceptible to such 95 changes, in size, shape and manner of assemblage as fall within the scope of the appended claim.

What we claim is:—

The combination of a hot water bottle 100 having a neck, a plug in the neck thereof having a concave wall about which the bottle neck is secured, said plug having a central opening with the outer end thereof enlarged to form an annular seat in said plug, 105 an interiorly screw threaded sleeve mounted in the enlarged end of the plug opening with the outer end of the sleeve flush with the outer end of the plug and the inner end of said sleeve spaced from the annular seat 110 in said plug, a gland screwed in said sleeve, a tube extending through said gland and

having the inner end thereof provided with a peripheral flange engaging the annular seat of said plug, and a washer interposed between the inner ends of said sleeve and 5 gland and the seat of said plug and compressible by said gland against the flange of said tube.

In testimony whereof we affix our signatures in presence of two witnesses.

WILLIAM B. SMITH.
VERNA D. SMITH.
